UNITED STATES PATENT OFFICE.

URIAH E. MILLER, OF HEILIG'S MILL, NORTH CAROLINA.

QUILTING-FRAME.

SPECIFICATION forming part of Letters Patent No. 406,929, dated July 16, 1889.

Application filed October 31, 1887. Serial No. 253,871. (No model.)

To all whom it may concern:

Be it known that I, URIAH E. MILLER, of Heilig's Mill, in the county of Rowan and State of North Carolina, have invented a new 5 and useful Improvement in Quilting Attachments for Sewing-Machines, of which the following is a specification.

My invention relates to quilting attachments for sewing-machines; and it has for its 10 object to provide such an attachment which may be readily connected and disconnected from the sewing-machine, which will be easy to handle and efficient in its operation.

It consists in a certain peculiar arrangement and combination of parts, which will be hereinafter fully described in the specification, and particularly pointed out in the 15 claims, reference being had to the accompanying drawings, in which—

20 Figure 1 is a top plan view of my improved attachment. Fig. 2 is a front view of the same. Fig. 3 is a rear view thereof. Figs. 4 and 5 are end views of the same. Figs. 6, 7, and 8 are detail views thereof. Fig. 9 is a 25 detail view showing one end of the roller G and its connection to the bracket F.

My invention consists, essentially, of two frames A C, one of which A forms the bed or fixed frame, which is attached to the sewing-machine table. The frame A consists of the longitudinal track-beams A' A² and the cross-pieces A³. The central portion of the beam A', between the central cross-pieces A³, is cut away, as at a² a², said portions being connected at their upper faces by a thin metal strip a', leaving a space d. The beam A' is also cut away, as at d', directly opposite the cut-away portion d in the beam A². By this construction it will be seen that the frame A 30 may be readily slipped in place upon the machine-table into proper position for operation. In applying the said frame to the sewing-machine table the same is arranged transversely across the machine-table. The metal strip a' is 35 slid under the presser-foot of the machine, the cut-away portions of the frame being of a distance equal to the width of the sewing-machine table. The frame A is then securely held in position by clamp-brackets f, provided with set-screws which bind against the 40 lower rear edge of the sewing-machine table,

the forward end of said frame being supported upon legs K, having adjustable feet L, whereby the height of said legs may be regulated to machine-tables of various heights, 55 said feet L being adapted to rest upon the floor.

In the upper face of the beam A² is formed a longitudinal groove a, which forms a track for a purpose hereinafter described. To the 60 outer face of said beam and near its rear end is journaled a wheel or pulley B, formed with a central circular recess b, in which recess is disposed a coiled spring b', one end of which is secured to the pulley B, while its opposite end is secured to a short shaft b⁶, projecting from the side of the beam A², and upon which shaft the wheel B is journaled. One end of a cord b³ is secured to the outer 65 periphery of said pulley, the outer free end of which is provided with a hook c, which is connected to the frame C, for the purpose presently explained.

C denotes the traveling frame, which consists of the longitudinal bars 1 2 and the 70 curved cross-bars 3 4. One end of the bar 1 is stopped short of the cross-bar 3 and is connected with said bar by a metal strip x, connected to the lower edges of said bars 1 3, thereby forming a space y between said bars. 75 By forming the space y in the bar 1, as described, the frame C may be readily slid under the presser-foot of the machine into its proper place upon the bed-frame A. Rollers h i are journaled under the bars 1 2, which 80 travel upon the bars A' A² of the frame A, the rollers i being beveled to fit in the track-grooves in the bar A² and thereby guide the said frame C in its movement upon said bed-frame.

j l denote metal bracket-plates secured adjustably upon the outer faces of the cross-bars 3 4. These plates each consist of a horizontal portion j', a forwardly and upwardly extending arm j², and an upwardly-extending slotted arm j³. The brackets j l are 90 adjustably secured to said bars by the set-screw k, forming a pivot for said brackets, and a similar screw k', which passes through the slotted arm j³, and by means of which the 95 brackets may be held in any desired adjustment on the bars 3 4. Rollers D are journaled 100

in the upper ends of the arms j^2 , and similar rollers D' are journaled in the upper ends of the slotted arms j^3 . These rollers are preferably formed of wooden cores covered with a 5 tin or other thin metal covering, and thus prevent the rollers from becoming split or warped.

The outer or front ends of the journals of the rollers D D' project slightly beyond the 10 bracket-plates and have secured thereon disks E E', provided with recesses $e e'$, in which are seated coiled springs $m m'$. These springs each have one end secured to the shafts of the rollers D D', while their other ends are secured to the disks E E'. The function of said disks and springs will be presently described. By reference to the drawings it will be observed that the horizontal portions j' of the brackets extend slightly below the curved 15 bars and have journaled in the inner lower edge thereof a roller D². This roller forms the pressing-roller, and it is arranged to operate just above the bed-plate of the sewing machine.

20 F F' denote adjustable bracket-plates pivoted at their forward ends to the cross-bars 34 by set-screws o, their inner ends being provided with an upwardly-projecting slotted arm F², through which pass set-screws o', 25 by means of which said plates may be adjusted in a desired position. The lower edge of the bracket F' is provided with an aperture F³, which forms a bearing for the journal g of the roller G, the opposite journal g' fitting into a slotted bearing F⁴, formed in the lower end of the bracket F. By this means the roller G, upon which the quilted material is wound after it has been sewed, may be readily detached from the bearings. 30

35 4c To hold said journal g' in place and also to prevent the take-up roller G from unwinding, I project said journal beyond the bracket F and provide it with a ratchet-wheel X, which is engaged by a spring-actuated arm p, secured upon said bracket F.

Near the plates F F' and to the upper faces of the cross-bars spring-plates H H are secured, which curve outward and downward, to the lower free end of which are connected 45 hooks Z, which are provided with chain-springs r, which are connected at their outer ends to plates S, provided with a series of teeth S', which are adapted to hook into the quilt being operated upon and stretch it laterally. 50

55 n n' are stops formed of spring-arms pivotally secured to the periphery of the disks E' E, which strike against the bracket-arms j^2 and j^3 when tension is being applied upon the springs $m m'$ and hold the said disks from 55 turning in one direction. To the inner face of the bar 4 and at the outer end thereof is secured a hook c, to which the free end of the cord b³ is attached.

The object of the disk B, and the spring connected therewith and connecting the disk with the traveling frame C, is for the purpose of making a self-feed to said frame C. It will

be observed that when the frame is pulled back the spring in the disk will be wound up, and while the machine is in operation the 70 spring is uncoiling and assists in pulling said frame C forward, and thereby takes at least one-fourth of the power exerted by the operator to run the machine, and thus makes the machine run lighter.

The operation of my improved quilting attachment is as follows: The base-frame A is first properly placed upon the sewing-machine table, the bar A² being disposed a short distance to the right of the needle-bar, the bar A' being to the left thereof. The lining or under part of the quilt is secured at one end to the roller D and smoothly rolled thereon. The top part or cover of the quilt is secured at one end to the roller D' and 80 smoothly wound thereon. The free ends of the lining and cover are then drawn together, passed under the pressing-roller D², and secured to the roller G. By making the brackets in which the rollers D D' D² are journaled 85 and the brackets in which the roller G is journaled adjustable it will be readily seen that the several rollers may be so adjusted as to accommodate the operation of said rollers on machine-tables of various makes, and also to 90 adjust the presser-roller D² to a greater or less pressure in relation to the take-up roller G. The several rollers having been properly filled with the lining and covering, the frame C is then slid under the presser-foot in place 95 upon the base-frame A. The roller G is then 100 also properly placed. The cord b³ is hooked to the frame C. Said frame is pulled back into place. The batting or other filling material is placed upon the lining between rollers D D', and the machine is then started, the seam being close up to the roller G, which is disposed just to the right of the needle. The hook-plates S are then hooked into the ends of the quilt, stretching the same laterally. 105 The springs within the disk tend to turn the rollers D D' in a direction reverse to the feed, and thereby always stretch the material in direction of its length, said tension being first applied to the spring by the gradual unwind- 110 ing of the material.

Having thus described my invention, what I claim is—

1. In a quilting attachment for sewing-machines, the combination, with the frame C and the take-up roller G, adjustably journaled therein, of the brackets $j l$, adjustably secured to said frame, said brackets consisting of horizontal portions j' , extended below said frame and forming bearings for the lower roller D², upwardly-extending arms $j^2 j^3$, projecting above the frame and forming bearings for the lining-roller D and covering-roller D', respectively, said brackets pivoted, as at o, and means for securing said brackets in proper adjustment, substantially as and for the purpose set forth.

2. The combination, with the frame C, of the brackets $j l$, adjustably secured to said

frame, said brackets consisting of horizontal portions j' , adapted to extend below said frame, said portions forming bearings for the lower roller D^2 , upwardly-extending arms $j^3 j^2$, provided with bearings for the roller D , and upwardly-extended slotted arms provided with bearings in their upper ends for the roller D' , said brackets being pivoted, as at o , and adjusted about said pivot by the screws o' , passing through the slotted arms, substantially as shown and described.

3. In a quilting attachment for sewing-machines, the carriage C and the quilting-fabric rollers, for the purpose specified, said carriage consisting, essentially, of the longitudinal

beams 1 2 and the transverse beams 3 4, one of said beams 1 being stopped short of the cross-bar 3 and connected to said bar by a metal strip X , forming a space Y between said bars, whereby the carriage is adapted to be 20 readily slipped under the needle-bar of the sewing-machine, substantially as and for the purpose described.

In testimony whereof I affix my signature in presence of two witnesses.

URIAH E. MILLER.
